UNITED STATES PATENT OFFICE.

CHARLES F. REYNOLDS, OF TOLEDO, OHIO.

DESIGN FOR A BUCKLE.

SPECIFICATION forming part of Design No. 25,860, dated August 4, 1896.

Application filed June 11, 1896. Serial No. 595,218. Term of patent 14 years.

To all whom it may concern:

Be it known that I, CHARLES F. REYNOLDS, of Toledo, in the county of Lucas and State of Ohio, have invented a new and original 5 Design for Buckles, of which the following is a full, clear, and exact description, reference being had to the accompanying drawings, forming part of this specification, in which—

10 Figure 1 is a top plan view of my design, and Fig. 2 is a longitudinal section on the line II II of Fig. 1.

My invention consists in a buckle having the form shown in the accompanying drawings and herein described.

15 As shown in the drawings, the buckle has parallel end bars 2 2, side bars 5 5, a cross-

bar 3 at or near the middle of the side bars, and a tongue 4, which extends from the middle of the cross-bar to the end bar 2. The 20 side bars are not straight, but are bowed inwardly and horizontally at the middle, where they are connected by the cross-bar and are also bowed vertically.

I claim—

25 The design for buckles substantially as herein shown and described.

In testimony whereof I have hereunto set my hand.

CHARLES F. REYNOLDS.
